LOCKING MEANS FOR LEVER OPERATED
ROTARY ACTUATING BARS OF DOOR
FASTENERSGeorge E. Dath, Mokena, Ill., assignor to W. H.
Miner, Inc., Chicago, Ill., a corporation of Delaware

Application July 5, 1947, Serial No. 759,238

6 Claims. (Cl. 292—218)

1

This invention relates to improvements in door fasteners of the rotary bar type, and more particularly to locking means for holding the bar against rotation with the doors fastened in closed position.

One object of the invention is to provide simple and efficient means for locking the lever operated bar of a rotary door fastener against rotation in opening direction after the door has been forced to its closed position by rotation of the bar.

Another object of the invention is to provide a door fastener for hinged doors comprising a rotary operating bar mounted on one of the doors and having keeper engaging means thereon engageable with fixed keepers to force the door open and closed, wherein the bar is rotatable through 180 degrees in forcing the door into and out of the door opening and is actuated by a handle lever for rotating the same, the lever being pivoted to the bar in such a manner that it may be dropped to pendant position when the door is closed, the lever being provided with a locking projection which is engaged with a fixed plate on the door when the lever is dropped to pendant position, thereby preventing rotation of the bar in door opening direction and maintaining the door tightly closed.

A further object of the invention is to provide a mechanism as set forth in the preceding paragraph wherein the locking projection of the lever and the fixed plate have wedging engagement with each other as the handle lever is swung to pendant position, thereby forcibly turning the bar to its final locking position.

Other objects of the invention will more clearly appear from the description and claims hereinafter following.

In the accompanying drawings forming a part of this specification, Figure 1 is an elevational view of the side wall of a railway car, provided with a door opening and having a pair of hinged doors for closing said opening, illustrating my improvements in connection therewith, the doors being shown in closed position and the operating handle lever being shown in its pendant position in full lines and in the raised horizontal position in dotted lines. Figure 2 is a horizontal sectional view, corresponding substantially to the line 2—2 of Figure 1. Figure 3 is a broken view, similar to Figure 1, on an enlarged scale, of portions of the doors at their meeting edges, the central portion of the operating bar, the operating lever for the bar, and cooperating locking plate. Figure 4 is a vertical sectional view, corresponding substantially to the line 4—4 of Figure 3. Figure 55

2

5 is a broken vertical sectional view, similar to Figure 4, with the operating bar and lever omitted, illustrating another embodiment of the invention.

5 In said drawings, 10 indicates the side wall member of a railway car, provided with a door opening 11, closed by the usual hinged doors 12 and 13. The doors 12 and 13 are supported along their outer edges by hinges 14—14 of well-known design. As will be understood by those skilled in this art, the hinged doors 12 and 13 are provided with beveled meeting edges, the edge of the door 12, which is the door last closed, overlapping the adjacent door 13.

15 The door 12 carries a rotary door fastener means of well-known design for forcing the door closed and also prying the same open, comprising a rotary operating bar 15 having keeper engaging crank members 16—16 at the top and bottom ends, cooperating with fixed keepers 17—17 on the car wall above and below the door opening, the keepers being provided with the usual cam slots within which the crank members engage. The bar 15 is rotatably supported by top, bottom, 20 and intermediate bearing brackets 18, 19, and 25, fixed to the door 12.

In carrying out my invention, as illustrated in Figures 1 to 4 inclusive, I provide broadly a combined actuating lever and locking member A, 30 which is hinged or pivoted to the operating bar 15 to be dropped to pendant position, and a locking or wedge plate B with which the locking portion of the lever A is engageable to lock the bar against rotation.

35 The combined lever and locking member A is of L-shaped form, having a barlike arm 21 provided with an outwardly offset hand grip portion 22 at its outer end, and a right angular portion at its inner end providing a locking finger or lug 23 extending laterally from said arm and projecting beyond the side of the bar 15 when the lever member A is dropped to its pendant position, as shown in Figures 1 and 3. The member A is supported on the bar 15 at the outer side thereof, 40 as seen in Figure 1, by a pivot pin 24 in the form of a rivet extending through the inner end portion of the lever member A and the bar 15, the pin 24 serving to hinge the lever member A for swinging movement in a vertical plane.

45 The locking or wedge plate B is in the form of a casting secured to the outer side of the door 12 to one side of the bar 15, the same being shown as disposed to the right of the bar, as seen in Figures 1 and 3, and in the path of movement of the finger or lug 23 of the combined lever and locking mem-

ber A. The front surface or face of the plate B is upwardly inclined away from the plane of the door 12, thus presenting a flat wedge face 25. At the upper end of the plate is an outstanding horizontal flange 26, which provides a limiting stop engageable by the lug 23 for arresting the pivotal movement of the lever member A.

In the closed and locked position of the doors 12 and 13, as shown in Figures 1, 2, 3, and 4, the keeper engaging crank members 16-16 of the operating bar 15 are in locking engagement with the keepers 17-17, and the combined actuating lever and locking member A is in the pendant position shown in full lines in Figure 1, with the locking lug or finger 23 in wedging engagement with the plate B. In the locked position of the parts, the bar 15 is effectively blocked against rotation in door opening direction, that is, rotation in counterclockwise direction, as viewed in Figure 2. To open the door 12, the member A is first swung upwardly to the horizontal dotted line position shown in Figure 1, thus disengaging the lug 23 from the wedge plate B. When the combined lever member A is swung to this horizontal position, the right angular lug 23 is withdrawn from its blocking position by being brought into alignment with the length of the bar 15, thereby permitting free rotation of the bar. The lever member A is then swung from left to right through an arc of 180 degrees to force the door partly open in the usual well-known manner by camming action of the keeper engaging crank members 16-16 and cooperating keepers 17-17.

In forcing the door 12 closed, the operation is substantially the reverse of that just described, the bar 15 being rotated in clockwise direction, as viewed in Figure 2, by swinging the lever member A from right to left, thereby camming the door shut. The operating lever member is then swung to its pendant position, bringing the lug 23 thereof into wedging engagement with the wedge plate B. As will be evident, this wedging action between the lever member A and the plate B imparts a further slight turning movement to the bar in door closing direction, thus forcing the keeper engaging crank members more firmly against the walls of the cam slots of the keepers and tightly locking the door.

Referring to the embodiment of the invention illustrated in Figure 5, the construction is the same as that illustrated in Figures 1 to 4 inclusive, with the exception that the locking cam plate, which is indicated by C and corresponds to the plate B hereinbefore described, is provided with retaining means for the lug of the combined actuating and locking lever A. As shown in Figure 5, the locking plate C has an outer wedge face 125, identical with the wedge face 25 of the plate B and a horizontal stop flange 126, similar to the flange 26. The flange 126 is provided with a depending, transversely extending lip 127 at its outer edge, which overhangs the wedge face 125 and is adapted to overhang the finger or lug 23 of the lever member A when the latter is dropped or swung to its pendant position with the door 12 closed.

I claim:

1. In a fastener for a door, the combination with a vertically disposed, rotary operating bar mounted on the outer side of the door; of means actuated by rotation of said bar in reverse directions for forcing the door open and closed; an actuating handle lever for rotating said bar, said lever being pivoted at its inner end to said bar for

swinging movement in a vertical plane, from horizontal position at right angles to said bar to pendant vertical position; a right angular arm on said lever extending radially from the pivot of said lever, said arm being rigid with the lever, said arm being aligned lengthwise with the bar when the lever is in horizontal position and being swingable with said lever outwardly at right angles to said bar when the lever is dropped to pendant position; and a locking plate fixed to said outer side of the door, said plate being in the path of movement of said arm when said lever is in pendant position for arresting movement of said arm to lock the bar against rotation.

2. In a fastener for a door, the combination with a vertically disposed, rotary operating bar mounted on the outer side of the door; of means actuated by rotation of said bar in reverse directions for forcing the door open and closed; an actuating handle lever for rotating said bar, said lever being pivoted at its inner end to said bar for swinging movement in a vertical plane, from horizontal position at right angles to said bar to pendant vertical position; an arm extending from the pivoted end of said lever, said arm being rigid with the lever, said arm being aligned lengthwise with the bar when the lever is in horizontal position and being swingable with said lever outwardly at right angles to said bar when the lever is dropped to pendant position; and a locking wedge plate fixed to the outer side of said door, said arm of said lever and said plate having wedging engagement with each other as the lever is dropped to pendant position to turn said bar in door closing direction and hold the same against rotation in door opening direction.

3. In a fastener for a hinged door, the combination with a vertically disposed rotary operating bar mounted on the door; of means actuated by rotation of said bar in reverse directions for forcing said door into and out of the door opening; an L-shaped actuating lever for rotating said bar, said lever having a long and a short arm, said lever being pivoted to the bar for swinging movement in a vertical plane, said long arm of the lever being swingable from horizontal position at right angles to said bar to pendant vertical position, said short arm being in vertical alignment with said bar when said long arm is in horizontal position, and being swingable to projecting horizontal position by swinging movement of said lever to pendant position; and a wedge plate on said door engageable by said short arm when swung to horizontal position to force said door tightly closed and lock the same in closed position.

4. In a locking means for a vertically disposed rotary bar of a door fastener for a hinged door, wherein the bar is mounted on the door, the combination with an actuating handle lever pivotally connected at its inner end to the operating bar for swinging movement in a vertical plane, said lever being movable from horizontal to pendant position; of a wedge plate on the door; and a locking lug on said lever, said lug being brought into engagement with said wedge plate by swinging movement of said lever to pendant position to turn the bar to force said door tightly closed and lock the same in closed position.

5. In a locking means for a vertically disposed rotary bar of a door fastener for a hinged door, wherein the bar is mounted on the door, the combination with an actuating handle lever pivotally connected at its inner end to the bar to be dropped to pendant position; a fixed wedge plate on the

door; and a projecting lug on said lever engageable with said wedge plate to lock the bar against rotation in door opening direction when said lever is moved to pendant position.

6. In a locking means for a vertically disposed rotary bar of a door fastener for a hinged door, wherein the bar is mounted on the door, the combination with an actuating handle lever pivotally connected at its inner end to the bar to be dropped from horizontal to vertical pendant position; of a fixed wedge plate on the door having an overhanging retaining lip thereon; and a projecting lug on said lever engageable with said

10 wedge plate in back of said lip to lock said bar against rotation in door opening direction when the lever is moved to pendant position.
